UNITED STATES PATENT OFFICE.

BURTT J. HUBBARD, OF KOKOMO, INDIANA.

CURTAIN-WINDOW CONSTRUCTION.

1,414,470.

Specification of Letters Patent. Patented May 2, 1922.

Application filed January 14, 1921. Serial No. 437,257.

To all whom it may concern:

Be it known that I, BURTT J. HUBBARD, a citizen of United States, residing at 1004 W. Sycamore Street, Kokomo, in the county 5 of Howard and State of Indiana, have invented certain new and useful Improvements in Curtain-Window Constructions, of which the following is a specification.

This invention relates to improvements in 10 vehicle curtain windows, and has for its object to provide means whereby a window may be mounted in a vehicle curtain, or other part of the vehicle cover, without the weight of the glass and frame causing the 15 curtain to sag, and also to provide means whereby a very neat and attractive mounting may be had by eliminating the appearance of the metallic ring or molding used in similar construction at the present time, 20 and which has a tendency to cut the cover material.

A further object is to provide a curtain window which may be more easily mounted in the curtain, and which can be manufactured more cheaply than windows in 25 present-day use.

Other advantages relating to various features of construction and arrangement will appear more fully hereinafter.

30 In the drawings—

Figure 1 is a broken view of a curtain, showing the window mounted therein;

Fig. 2 is a view taken on the line 2—2 of Fig. 1, showing the means for mounting 35 the same between the cover material of the curtain and the lining thereof;

Fig. 3 is a similar sectional view, showing the welts constructed in a single piece; and

40 Fig. 4 is another form of window having the inner welt constructed of sheet metal.

Similar reference characters refer to similar elements in the several views of the drawings, in which—

45 10 is a curtain immediately surrounding the window 11, which may be of any desired size and which is shown mounted in a frame 12, of any desired shape, and preferably of wood. This frame is reinforced 50 with an annular strip of metal 13, beneath which at its uppermost and lowermost points are slots 12^a cut in the frame, through which strips 14, of webbing or the like, are inserted. These strips extend between the 55 outer covering material and the lining of the curtain, and are attached to the frame of

the top and bottom of the car curtain in any suitable manner. The weight of the glass, frame, and welts which hold the glass in place in said frame is thereby removed 60 from the curtain.

The frame 12 is slightly rounded at its edges, as shown, to prevent wear on the lining and covering material, and has two holes 12^b therethrough, whereby said frame 65 may be properly positioned between said covering material 10 and lining 9 with respect to the opening therethrough, within which the window is mounted.

The glass is held in place by an outer and 70 inner welt, indicated generally in Fig. 2 by the numerals 15 and 16, respectively, said welts being so relatively constructed as to form an annular groove, within which the glass is securely held. The outer welt 15 75 consists of a core 15^a, of wood, metal, or other suitable material covered with material similar to the curtain covering material 10. This material is wrapped around the core 15, and the edges are folded together, as shown, and secured in position on the inner periphery of the frame 12 by nails or screws 17. The inner welt, indicated by numeral 16, consists of a core 16^a of material corresponding to that of which 80 the core 15^a of the outer welt 15 is composed, and a covering 16^b of material similar to the lining 9 of the curtain. The inner welt 16 is held in position on the inner periphery of the frame 12 by the same means 85 as those employed in securing the outer welt 15 in place, as shown in Fig. 2. The outer welt is shown circular in cross section, and the inner welt is shown rectangular in cross section, but it will be understood that they 90 may be of other shapes.

Assuming that the frame 12 is properly held in position by the webbing 14, the outer covering material 10 is then folded over the inner periphery of the frame and tacked 100 thereon, as shown in Fig. 2. The outer welt 15 is then placed in position, the edge of the core-covering material 15^b being placed over the stepped surface of the frame formed by folding the outer covering material thereon, as above described. This proper positioning is effected by placing upon the lining and covering materials of the curtain, by use of a suitable pattern, or the like, certain marks corresponding to the holes 105 12^b of the frame 12. In assembling the frame and curtain the workman positions

the frame in such manner that the holes 12^b thereof register with the marks previously placed upon the curtain material as above described. By this simple process the 5 proper positioning of the frame 12 with respect to the opening provided in the curtain materials 9 and 10 is assured. The lining 9 is then folded over the edge of the core-covering material 15^b of the outer welt 10 and nailed in place. The glass is then placed in position and secured by the inner welt 16, which is held in place by nails or screws which pass through the folded over portion of the lining and through the edge 15 of the core-covering material covered with material 15^b of the welt 15 into the frame 12, as clearly shown in Fig. 2. The object of folding the lining over the edge 15^b is to hide the latter from view, thus giving 20 a neater appearance to the window than if a different construction were employed.

In the modification shown in Fig. 3 the welts are constructed in one piece, and may be of either leather, metal, or other suitable 25 material. In this construction the welt has two beaded portions covered with top and lining material, as in the form previously described, or it can be covered with top material alone or provided with suitable finish, 30 the covering being omitted. These welts are held in place by nails or screws passing through holes in the inner welt portion and entering the wooden frame, as shown. The method of suspending the glass and frame 35 by the use of webbing is the same as that employed in the construction illustrated in Fig. 2. The assembling of the glass and welt, before the same is placed in position in the frame, will be necessary where the 40 one-piece welt construction is employed, as will be clear.

In the form shown in Fig. 4 the frame 12 is suspended in the manner described above, but the outer welt 15 consists of a 45 core 15^a of sheet metal, having a roll 15^c and a flange 15^d, as shown. This core is covered by covering material 15^b, which corresponds to the covering material 10 of the curtain. The welt is secured in position 50 in the frame by means of nails or screws which pass through the flange 15^d of the core 15^a. The inner welt 16 may be constructed in the same manner as the inner welt described in connection with Fig. 2.

55 The welts described may be used where no lining is used in the vehicle curtain, by covering the frame 12 with material to correspond with the inner side of the covering material and permitting the supporting 60 webbing 14 to show.

It will be seen that in each form of the construction described a neat appearing window is the result, the nails by which the covering material is secured to the frame 65 being hidden by the outer welt, which, in

turn, is securely held in position by the same nails by which the lining material and inner welt are secured.

Although I have shown and described three forms of my invention for purposes 70 of illustration, it will be apparent that other modifications may be made without departing from the scope of the invention as defined in the appended claims.

I claim:

1. In combination with a curtain or the like comprising a covering and a lining, a frame, a reinforcing band extending around the outer periphery of said frame supporting means attached to said band, 80 and a light element mounted in said frame.

2. In combination with a curtain or the like comprising a covering and a lining, a wooden frame suspended between said covering and said lining, a metal reinforcing band extending around the outer periphery of said frame, a light element, and welts securing said light element in said frame.

3. The combination with a curtain or the like of a window comprising a frame, a 90 light element carried thereby, a band surrounding said frame and looped strips secured by said band to said frame.

4. The combination with a curtain or the like of a window comprising a frame, a 95 light element carried thereby, a band surrounding said frame, said frame having notches therein beneath said band, and looped strips extending through said notches in said frame.

5. The combination with a curtain or the like comprising a covering and a lining and having an aperture therein, of a frame, said covering and lining elements adjacent said aperture being turned with respect 105 to said frame, an outer and an inner welt, one of said welts being enclosed in flexible material, said flexible material overlying the turned portion of one of said curtain elements and partly underlying the turned portions of said other curtain element, and a light element mounted between said outer and inner welts.

6. In combination with a curtain or the like comprising covering and lining members, a frame supported between said members adjacent an opening therein, said curtain members being turned with respect to said frame, a welt overlying the turned portion of one of said curtain members, 115 the turned portion of said other curtain member overlying a portion of said welt, a second welt overlying the turned portion of said last mentioned curtain member, and a light element carried between said 120 welts.

In testimony whereof, I have subscribed my name.

BURTT J. HUBBARD,
